UNITED STATES PATENT OFFICE.

PHILIP LINDEMAYER, OF BALTIMORE, MARYLAND, ASSIGNOR TO THE MARYLAND STOPPER COMPANY, OF SAME PLACE.

DESIGN FOR A BOTTLE.

SPECIFICATION forming part of Design No. 33,364, dated October 16, 1900.

Application filed September 20, 1900. Serial No. 30,631. Term of patent 7 years.

To all whom it may concern:

Be it known that I, PHILIP LINDEMAYER, a citizen of the United States, residing at Baltimore, in the State of Maryland, have invented and produced a new and original Design for Bottles, of which the following is a specification, reference being had to the accompanying drawings, forming part thereof.

Figure 1 is a side elevation of a bottle, showing my new design. Fig. 2 is a partial central longitudinal section of the same. Fig. 3 is a plan of the bottle.

As shown in the drawings, the leading or material feature of my design consists of a series of facets disposed about the mouth of the bottle. As represented, these are in the form of scallops.

2 denotes the convex portions of the bottle-neck, and 3 the concave portions of the

said scallops. On the neck of the bottle is a 20 circumferential groove 4, and at the center of the bottom of said groove is a second narrower circumferential groove 4'.

5 denotes the shoulder of the bottle, and 6 its body.

Having described my invention, what I claim as new, and desire to secure by Letters Patent, is—

The design for a bottle, as herein shown and described.

In testimony whereof I have signed my name to this specification in the presence of two subscribing witnesses.

PHILIP LINDEMAYER.
